PACKING PAD

Robert W. Burrows, Petaluma, Calif.; Mabel Burrows, executrix of said Robert W. Burrows, deceased, assignor to William K. Jaquith, Petaluma, Calif.

Application September 28, 1931, Serial No. 565,473

8 Claims. (Cl. 217—3)

This invention relates generally to a packing pad or buffer which is adaptable to use in cushioning the inner faces of a box container for packing fruit and the like, and is related to 5 my co-pending application Serial No. 475,020, filed August 13, 1930, for Packing pads.

Broadly speaking, the invention consists of a plurality of overlying flaccid sheets having up-formed portions and a reinforcing back sheet 10 member which may extend arcuately beyond the edges of the flaccid sheets. The reinforcing back sheet portion is intended to abut the inner face of a box or crate wall, while the opposite side of the pad which may be called its 15 face abuts the fruit or box contents and is formed of the flaccid sheets which are soft and pliable.

In order that the advantages of this invention may be readily distinguished from the known 20 art, it is to be understood that in referring to flaccid sheets as distinguished from corrugated board, what is meant is material which when cut in small elongated pieces will sag of its own weight, as more fully set forth in my said co-pending application.

These up-formed portions will increase the cross sectional thickness of the paper depending on the coarseness of the portion which is up-formed, and I prefer to use up-formed portions 30 of such coarseness so that the extreme transverse planes of the sheets so formed increase the normal thickness of the paper about four-fold. The up-formed portions in the paper are irregularly spaced and preferably irregular in 35 size so that when the layers of the flaccid sheet are in overlying or superposed relationship, the up-formed portions or indentations, as the case may be, do not nest and in that manner they form a pad about four times the normal thickness 40 of the paper, the up-formed portions spacing the normal plane of the adjacent sheets and thereby forming a cushion body which is soft and flexible.

In the fruit business, it is customary to pack 45 the fruit in boxes of well known type, made of side pieces of relatively thin material, such as wood panels or slats fastened to shock ends, and a top panel or slats, the boxes being usually referred to as crates or lugs.

50 In commercial practice it is also customary to fill said crates or lugs until the fruit extends beyond the upper edge of the filling opening of the box for the double purpose of absorbing any settling of the fruit in transportation, and 55 so that the container presents the appearance

to the customer of being full weight and liberal in quantity. When the top panel or slats are fastened on the crate prior to nailing at the ends, the panels or slats arch at the center, and since these top pieces are usually flat pieces of 60 thin wood board, there is a downward pressure upon the fruit, both at the time of fastening the top and also thereafter. This pressure upon the fruit causes the upper layer of fruit along the sides of the box to be bruised or cut by the 65 upper edge of the box side.

As set forth in my co-pending application above referred to, it is desirable that a pad for packing fruit and like delicate products should be soft and flexible, and sufficiently economical 70 to manufacture so as not to lay an undue financial burden upon the packed product, the said co-pending application making provision for a packing pad comprised of a plurality of overlying sheets of flaccid material having up-formed 75 portions and provided with a facing sheet of water-proof material, said sheets being secured in overlying relationship.

It is an object of the present invention to 80 provide a packing pad having a soft flexible portion to serve as a crate liner and a more rigid portion at the back to serve as a reinforcement of the flexible portion for convenience in handling; other objects are to provide a flexible packing pad which is economical to manufacture and the handling of which is facilitated by a reinforcing sheet of material at the back more rigid than the composition of the pad. Another object is to provide a packing pad having a portion 85 with an arcuate edge adapted for extending above the side edges of a packing crate. A further object is to provide a packing pad of overlying sheets of flaccid material with portions up-formed from the normal transverse plane of the sheets, so as to avoid nesting of the up-formed 90 portions, and to provide in connection therewith a reinforcing means which also serves to guide over-filled quantities of fruit past the sharp upper edge of a crate side wall.

With the above mentioned and other objects 100 in view, the invention consists in the novel construction and combination of parts herein-after described, illustrated in the accompanying drawing and pointed out in the claims hereto appended; it being understood that various changes in the form, proportion, size and minor details of construction within the scope of the claims may be resorted to without departing 105 from the spirit or sacrificing any of the advantages of the invention.

To more clearly comprehend the invention, reference is directed to the accompanying drawings, wherein:—

Fig. 1 is an elevation of one face of pad, being the back face which abuts the crate walls.

Fig. 2 is side edge view of a fragment of one sheet of pad forming material, enlarged in thickness.

Fig. 3 is a perspective of packing crate, showing manner of placement of pad.

Fig. 4 is a vertical transverse section of pad with facing sheet and with back reinforcing sheet having top extension.

Fig. 5 is a vertical transverse section of pad showing an extension member at top.

Fig. 6 is a vertical transverse section of pad having reinforcing backing sheet.

Referring to the drawing in which like characters of reference designate similar parts in the several figures, 10 represents a pad generally, which is composed of a plurality of overlying layers of sheet material 11, which has up-formed portions 12 from the normal plane 13 of the sheet. For this purpose I prefer to use paper, which is well known commercially as crepe paper, which is manufactured with crinkles formed and haphazardly positioned therein, so that the surface thereof is provided with a large number of irregularly placed and irregularly sized projections or ridges 12 and indentations or valleys 14, the irregularity in size and placement of ridges and valleys avoiding register of the ridges and valleys in adjacent overlying sheets. These projections or ridges 12 provide the up-formed portions referred to in the description and claims of this application, and may be on either or both sides of the normal plane of the sheet, and while preferably haphazardly positioned, may also be symmetrically positioned, provided nesting is avoided in adjacent overlying sheets. It is represented that the sheets be soft, flexible, or flaccid, as distinguished from sulphite chip board, commonly called corrugated board, which is relatively stiff and hard.

These overlying sheets 11 may be secured in pad forming relation by any suitable means, such as gluing at their edges, but my preferred means of relatively positioning said sheets is to provide a facing sheet 15 preferably of waterproof material, such as may be produced by a paraffined coating on paper, and passing said facing sheet around the two lengthwise edges of the flaccid sheets and gluing same on the reverse side of the pad leaving the ends of the pad with free edges, as indicated at 16, thus eliminating any glue from possibility of contact with the fruit. This is most clearly shown in Fig. 1, and enables the making of the pads in long strips to be cut in desired lengths.

It will be realized that the pad thus far described is of a very flexible nature, and as a practical matter it is necessary to handle these pads rapidly, and also to place them in boxes before the fruit is packed therein, and, therefore, it is desirable to have a reinforcing backing sheet member so that the pad will not sag in the box while the fruit is being packed, and also to provide a reinforcing means to prevent injury of the pads. For this purpose, a backing sheet 17 of material, more rigid than the flaccid sheets, may be placed along the rear side of the over-lying flexible sheets, in which event the portion of the facing sheet overlapping the rear side of the pad may also include within its

fold the edges of the reinforcing backing sheet, as best shown in Fig. 6.

It is preferred, however, that the reinforcing sheet 17 extend beyond one edge of the flexible pad providing a portion 18 which has its free edge formed arcuately, as at 19 in Fig. 1, and as shown in section in Figs. 4 and 5. This arcuate portion provides a filler for the gap which exists between the upper edge 20 of the box side and the crown of the arc 21 formed by the lid panel or slats 22.

Normally, the flexible portion of the pad will extend a short distance above the upper edge 20 of the side of the box, as indicated at 23, so that when the extended portion 18 of the reinforcing member guides the fruit downwardly, either from vibration in transportation or by the pressure of the top 22, the fruit will bear against a cushion pad at the upper edge of the box side instead of upon the sharp edge of the box, or upon a hard surface which would be present were it not for the flexible cushion pad interposed between the fruit and the back reinforcing sheet 17.

In Fig. 1 is shown a modified form of pad providing for a combination side wall pad and end pad and in which a great saving in material and cost is made by reinforcing the back of the flexible pad with the reinforcing backing sheet adjacent the longitudinal pad edges only, the portion A being intended for the side of the box and the portion B being intended for the end of the box. In this modified form, the upper reinforcing member 24 is not provided with an extending portion, such as 18, for the reason that the top of the box fits closely upon the end shooks, and the portions A and B when within the box, being at an angle of substantially 90°, are substantially self supported. In this modified form of Fig. 1, it is optional to also provide a strip 25 parallel with and adjacent to the bottom edge of the pad. Manifestly, the pad shown in Fig. 1 could be severed on the line marked c—c and the severed sections used separately. However, for purposes of economy of labor and expense in packing fruit, it is preferred that the pad shown in Fig. 1 should be of sufficient longitudinal length to reach along a side and across an end of a fruit crate.

Having thus described the invention what is claimed as new and desired to be protected by Letters Patent is:—

1. A packing pad comprising a plurality of flaccid sheets in overlying relationship and having portions up-formed from their normal planes providing ridges and valleys, and a backing sheet of material more rigid than the flaccid sheets, said sheets being relatively held at two edges.

2. A packing pad comprising a plurality of overlying flaccid sheets having up-formed portions providing ridges and valleys, and a facing sheet having at least one dimension greater than the other sheets, and a backing sheet of material more rigid than the flaccid sheets, said greater dimension portion of the facing sheet being adapted for folding over the corresponding edge portions of the other sheets and for attachment to the opposite side of the backing sheet.

3. A device of the character described comprising a plurality of overlying flaccid sheets in pad forming relation, said flaccid sheets having portions of their respective bodies up-formed from the normal transverse plane of the sheets

providing ridges and valleys, the adjacent sheets having ridges and valleys out of register so as to avoid nesting of the ridges and valleys of adjacent sheets, and a strip of material more rigid than the flaccid sheets positioned adjacent an edge of the flaccid sheets so as to leave an area of the flaccid sheets free of the rigid material, said rigid material having a portion extending beyond the edge of the flaccid sheets, 10 said extended portion having an arcuately formed edge portion, said sheets being secured together.

4. A device of the character described comprising a plurality of overlying flaccid sheets in pad forming relation, said flaccid sheets having portions of their respective bodies up-formed from the normal transverse plane of the sheets providing ridges and valleys, the adjacent sheets having ridges and valleys out of register so as to avoid nesting of the ridges and valleys of adjacent sheets, and a sheet of material more rigid than the flaccid sheets positioned parallel of the flaccid sheets and having an arcuately formed edge portion which extends beyond a portion 25 of the edge of the flaccid sheets and said flaccid sheets having an edge portion which extends beyond an edge portion of said rigid sheet.

5. A device of the character described, comprising a plurality of overlying flaccid sheets in pad forming relation, said flaccid sheets having portions of their respective bodies up-formed from the normal transverse plane of the sheet providing ridges and valleys, the adjacent sheets having ridges and valleys out of register so as 30 to avoid nesting on the ridges and valleys of adjacent sheets, and a strip of material of lesser transverse width and more rigid than the flaccid sheets, secured to said overlying flaccid sheets adjacent an edge thereof, and having a portion extending therebeyond, said 35 extended portion having an arcuately formed edge portion, said flaccid sheets and said strip being secured in juxtaposition.

6. A device of the character described, com-

45

prising a plurality of overlying flaccid sheets in pad forming relation, said flaccid sheets having portions of their respective bodies up-formed from the normal transverse plane of the sheet providing ridges and valleys, the adjacent sheets having ridges and valleys out of register so as to avoid nesting of ridges and valleys of adjacent sheets, and a strip of material of lesser transverse width and more rigid than the flaccid sheets secured to said overlying flaccid sheets adjacent the edge thereof and having a portion extending beyond the edge of the flaccid sheets, and a portion lying substantially parallel to the edge portion of the flaccid sheets, said extended portion being provided with an arcuate free edge.

7. A device of the character described, comprising a plurality of overlying flaccid sheets in pad forming relation, said flaccid sheets having portions of their respective bodies up-formed from the normal transverse plane of the sheet providing ridges and valleys, the adjacent sheets having ridges and valleys out of register so as to avoid nesting of ridges and valleys of adjacent sheets and a strip of material of lesser transverse width and more rigid than the flaccid sheets secured to said overlying flaccid sheets adjacent the edge thereof and having a portion extending beyond the edge of the flaccid sheets, and a portion lying substantially parallel to the edge portion of the flaccid sheets, said extended portion being provided with an arcuate free edge, the extended portion being positioned so that an edge of the flaccid sheets forms a chord of the arc of the extended portion.

8. A packing pad comprising a flexible body portion, a more rigid portion mounted on the flexible body portion adjacent an edge thereof and having a portion extending beyond an edge of the flexible portion, said extended more rigid portion having an arcuate edge, the said flexible portion and said more rigid portion having overlying area relative to each other.
